DESIGN FOR A PLAQUE

George F. Otte, River Rouge, Mich.

Application October 19, 1942, Serial No. 108,555

Term of patent 7 years

To all whom it may concern:

Be it known that I, George F. Otte, a citizen of the United States of America, residing at River Rouge, in the county of Wayne and State of Michigan, have invented a new, original, and ornamental Design for a Plaque, of which the following is a specification, reference being had therein to the accompanying drawing, forming a part thereof, wherein:

I claim:

The ornamental design for a plaque, substantially as shown.

GEORGE F. OTTE.
